UNITED STATES PATENT OFFICE

MEYER REINGOLD, OF BROOKLYN, NEW YORK

WATERPROOF OVERALLS

Application filed February 16, 1931. Serial No. 516,236.

This invention relates to the class of garments of the overall type, and has especial reference to what is known as a one-piece overall garment made of waterproof material and which may be used advantageously by 5 motor cycle riders.

The garment of the present invention embodies improved features of construction rendering it weatherproof, particularly to 10 keep out rain, and which may be donned and removed in a convenient manner.

The present garment is particularly adapted to exclude moisture and rain water at the front of the body section thereof when the 15 wearer is riding a motor cycle, and is also adapted to shed water at the back so as to keep it from getting on the seat.

The improved features of construction make the garment of the present invention 20 neat in appearance and give to the wearer freedom of movement particularly when sitting.

The nature of the invention and its distinguishing features and advantages will appear when the following specification is read 25 in connection with the accompanying drawings, in which

Figure 1 is a view of a garment having the 30 features of the invention shown;

Fig. 2 is a back view of the garment;

Fig. 3 is a side view of the garment showing the rear panel thrown back to illustrate 35 one of the side gussets;

Fig. 4 is a view similar to Fig. 3 showing the rear panel fastened to the front of the 40 body section, and also showing the manner in which the side gusset folds;

Fig. 5 is an enlarged section on the line 45 5-5 of Fig. 4;

Fig. 6 is a fragmentary section of the 50 garment showing the portions which cover the lower body and thighs of a person, while the person is sitting;

Fig. 7 is a fragmentary front view of the 55 neck placket and collar construction shown opened.

The garment of the present invention is made preferably of waterproof material, such as fabric and rubber composition, or any other material or combination of materials.

The parts of the garment may be secured to each other, or be fastened together according to known methods of manufacture.

In accordance with one feature of the invention, the body section 10 of the garment 55 has no openings in the front thereof, or, in other words, the front of the body section is closed from the crotch to a point near the top to form an opening sufficiently large for the head of the wearer to pass therethrough 60 when donning the garment. In the present instance there is formed a closed seam 11 from the crotch of the garment to a point near the top for the stated purpose. The seam 11 may be formed by vulcanizing the front 65 pieces 12 which form the upper front of the body section and the front of each of the leg sections 13. Incidental to the closed front construction of the body section 10, there is provided an opening in the top of the body 70 section, which opening is partly bordered by a collar 14 and also is partly closed by a front placket 15. The placket may be closed or buttoned by suitable securing or fastening 75 means, such as coactive snap fastener elements 16 and 17 on the meeting edges of the front pieces 12. The neckband 18 of the collar 14 may be of tubular construction to receive therethrough a tying cord 19.

In accordance with another feature of the 80 invention there is provided a depending panel 20 at the back of the body section 10. This panel 20 extends between the shoulders of the body section, and extends from the neckband to a point below the seat 21. The lower 85 end of the panel 20 is left free or unsecured, thus leaving an opening in the back of the body section between the panel 20 and the seat 21.

In accordance with another feature of the 90 invention, gussets 22 are secured in place in any suitable manner between the rear edges of the front pieces 12 and the side edges of the panel 20. Each gusset 22 extends up to the related armhole seam and is substantially of 95 triangular shape. These gussets 22 give fullness to the body section 10 of the garment and make it possible for the wearer to readily don the garment and to remove it. Each gusset 100 is taken up or fastened in a folded condition

by suitable fastening means, such as coactive snap fastener elements 23 and 24 on the related gusset near the panel side edge, and the related front piece 12, respectively. The folded condition of each gusset 22 is shown in Figs. 4 and 5.

In accordance with another feature of the invention, the upper part or top of the seat 21 extends well up, to be disposed slightly above the wearer's waist line, and this upper part is gathered and has secured in relation thereto elastic means, such as an elastic band 25 to make the upper part or top of the seat snugly fit the wearer's back.

15 The wearer dons the garment by stepping into it by reason of the opening in the back. The wearer slips on the leg sections and then brings the head up into the body section 10 through the opening in the top thereof. The 20 gussets 22 are then fastened to bring the panel 20 closer to the body of the wearer. The placket 15 is then closed by engaging the elements 16 and 17, after which the string 19 may be tied, drawing the collar 14 snugly 25 about the neck of the wearer.

From the foregoing it will be obvious that the garment will present a weatherproof front body section which will exclude water; that the panel 20 at the back will shed water and 30 that it is particularly advantageous for this purpose when the wearer is in a sitting position, since the panel extends down below the seat section on the outside thereof; and that the garment will be neat in appearance.

35 Claims:

1. A garment of the class described including a body section closed at the front except at the top for the purpose of accommodating the head of the wearer, said body section 40 having a seat portion which extends upwardly at the back, there being an opening in the back of the body section above the seat portion, the body section having a depending weathering panel at the back which 45 covers and extends below said opening at the outside of said seat portion, said opening enabling the wearer to get into and out of the garment, and gussets joining the body section with a panel to let the latter out to give the desired fullness while the wearer is 50 getting into and out of the garment.

2. A garment of the class described including a body section having a seat portion which extends upwardly at the back of said 55 section, there being an opening in the body section above the seat portion, said body section also having a depending panel which covers and extends below said opening and partly over the seat portion at the outside of 60 the latter, gussets joining the side edges of the front portion of the body section with the side edges of the panel and each gusset extending from a point above the lower edge of said panel to the related armhole seam of 65 the body section, to give fullness to the body

70 section at the opening, and means to retain the gussets folded and also to keep the panel close to the seat portion.

3. A garment of the class described including a body section having a seat portion which extends upwardly at the back of said section, there being an opening in the body section above the seat portion, said body section also having a depending panel which covers and extends below said opening and 75 partly over the seat portion at the outside of the latter, and gussets joining the side edges of the front portion of the body section with the side edges of the panel and each gusset extending from a point above the lower edge 80 of said panel to the related armhole seam of the body section.

4. A garment of the class described including a body section having a seat portion which extends upwardly at the back of said section, there being an opening in the body section above the seat portion, a depending panel integral with the back of the body section which covers and extends below said opening on the outside of the seat portion, gussets joining the side edges of the front 85 of the body section and the panel to let the latter out to give the desired fullness for donning and removing the garment, and co-acting means on the body section and gussets 90 whereby to detachably fasten them together.
